METHOD AND APPARATUS FOR HEATING FLUIDS

Filed Dec. 29, 1923

UNITED STATES PATENT OFFICE

SIDNEY P. VAUGHN, OF ACKERMAN, MISSISSIPPI

METHOD AND APPARATUS FOR HEATING FLUIDS

Application filed December 29, 1923. Serial No. 683,399.

(GRANTED UNDER THE ACT OF MARCH 3, 1883, AS AMENDED APRIL 30, 1928; 370 O. G. 757)

My invention relates to the heating of fluids generally, and while the characteristics described herein may be advantageously employed for other purposes than generation of steam, such as for heating air, water, or other fluids, my invention applies particularly to that type of apparatus known as the flash type water tube boiler, and the term "boiler" will be used generically throughout this specification in describing the fluid containing element encircling the combustion chamber as a means for simplifying the description of the invention.

An object of my invention is to provide means in the combustion chamber of a boiler for converting the heat of the combusting fuel into radiant heat and transfer the heat to the fluid containing element or boiler by radiation in a rapid and efficient manner.

Another object of my invention is to provide a primary combustion chamber for the initial combustion of the more volatile constituents of the fuel which will cause said fuel to combust very rapidly and to crack or

volatilize the less volatile constituents of said fuel and at the same time keep the flame from contact directly with the fluid containing element while in said chamber; and to provide a secondary combustion chamber,

preferably surrounding said primary chamber, and whose outer wall is preferably formed wholly or largely by said fluid containing element, and in which secondary chamber the combustion continues in close contact and proximity with a wall of said element, fresh air being supplied to said secondary chamber to promote complete combustion therein. From said secondary chamber the combustion products are preferably carried over one end of said element and into one end of a flue preferably surrounding said element, and in which flue the combustion products are carried in direct contact with a surface, and throughout substantially

the length of said element, where said combustion products are carried over the adjacent ends of said element and chambers to a centrally disposed outlet, said flue being provided preferably with multiple vertical baffles to facilitate the equalization of the

draft of said outlet between each of said baffles.

Another object of my invention is to provide an apparatus by which a supply of heated fluid may be economically maintained at substantially a uniform temperature, and in the case of a gaseous fluid at substantially a uniform pressure also, notwithstanding instantaneously varying demands upon such supply.

Another object of my invention is to provide, as an integral step in my invention, a method of and apparatus by which the temperature of the steam in the main steam line leading from the boiler to the main power unit regulates thermostatically the supply of feed-fluid and maintains a varying fluid level in the boiler according to the desired temperature of the steam to be used by the main power unit and without substantial and disrupting shocks of such fluid upon the high-pressure boiler and fluid feed pump due to my eliminating the sudden changes of pressure of said fluid upon said boiler and pump as follows:

Supplementing, and as a check upon said thermostatic or other control, I further eliminate said sudden pressure changes by bypassing the fluid supplied by the pump around said thermostatic control and conveying said fluid from said by-pass through a check-valve and then an air dome before it enters said boiler; and a still further supplement to and check upon said thermostatic control and said check valve is provided by me by conveying the feed from said pump through a second check-valve and thence to said first check-valve, said second check-valve being adapted to discharge into a pipe or channel leading from the discharge side of said thermostatic controlled valve to the intake side of said pump.

Another object of my invention is to provide a vapor generator containing a high pressure and a low pressure boiler within the same unit, and heated by the hot gases after having supplied their main heat to said high pressure boiler; and by which the feed-fluid to be evaporated in the high pressure boiler is previously evaporated in the low pressure boiler and condensed to remove all

impurities that may injure the high pressure boiler, and means in the low pressure boiler by which the scale formed, and other impurities, therein may be readily removed without disturbing the other parts of the steam generator.

Other advantages of my invention will be apparent from the following detailed description, when taken in connection with the accompanying drawings; in which,

Fig. 1 is a diagrammatic view partly in side elevation and partly in section, of the complete apparatus; Fig. 2 is a plan sectional view of the generator forming a part of the apparatus; Fig. 3 is a vertical sectional view of a modified form of generator for the apparatus, showing the fuel nozzle and opening in the lower part of the combustion chamber instead of in the top part.

Referring to the drawings more in detail the vapor generator of the apparatus consists of a suitable metallic casing 1 with a suitable heat insulating lining 2, enclosing a boiler 3, in the form of a cylindrical helical coil of tubing, encircling a central primary combustion chamber "A" and an annular secondary combustion chamber "B" separated from each other by a wall 4 with small openings therein, and which is supported by a cross member 48 securely fastened to the lower part of the casing. The wall 4 is in the form of a mantle or grill enclosing the primary combustion chamber and is made of any suitable material with a high fusing point. Both ends of the primary combustion chamber "A" are closed with the exception of a small opening 5 in one end through which fuel and air are supplied to the combustion chamber. On the left side of the center line of the combustion chamber I show the walls thereof as being in the form of a grill in which the rectangular openings 8 connect the primary combustion chamber "A" with the secondary combustion chamber "B", and slant outward in an upward direction to prevent the escaping gases of combustion making a right angle contact with the boiler. Broken fragments 7 of refractory material are placed in the bottom of the combustion chamber which become incandescent in the process of combustion and assist in promoting the combustion of the incoming fuel.

An annular down draft flue 10 is formed within the casing between the lining thereof and the boiler for the escape of the hot gases thrown off by the secondary combustion chamber. The secondary combustion chamber is closed at the bottom, but has small openings 46 formed therein for supplying an additional quantity of air to the fuel when required. This closure causes the gases of combustion in the secondary combustion chamber to pass over the top of the boiler 3 thence downward in the down draft flue 10,

in a direction opposite to the incoming liquid to be heated. Vertical angular vanes 9 (formed preferably of uniform angularly crimped sheet, preferably of copper, extending completely around and throughout substantially the length of flue 10) are suitably arranged in the down-draft flue 10 to absorb heat from the gases and transmit it to the boiler by convection and radiation. Suitably arranged in the bottom of the casing I provide a chamber 48a which connects the down-draft flue 10 with a discharge opening 47 in the bottom of the casing.

The mantle or grill wall 4 enclosing the primary combustion chamber absorbs heat from the gases of combustion, becomes incandescent, and radiates the heat of the fuel to the boiler, in the same manner as an ordinary gas mantle would if surrounded by a liquid containing element.

I provide a fuel heating and feed system for light hydro-carbon fuels in which the fuel is supplied under pressure from any suitable source through a fuel line 17 to a coiled vaporizing unit in an opening 5 in one end of the combustion chamber. Connected with said fuel heating unit is a fuel nozzle 18 so placed over the opening 5 that it will direct the heated fuel through substantially the center of opening 5 and into the primary combustion chamber and cause the vaporized fuel to carry with it a sufficient supply of air to complete combustion. As a means for regulating the supply of fuel I provide a needle valve 16, in the fuel line 17, which is actuated through a valve stem 15 by a diaphragm regulator 14 acted upon by the pressure within the boiler. Normally, the valve is held open by a spring pressing downwardly upon the diaphragm, which permits the fuel to pass into the combustion chamber, but when the pre-determined working pressure of the boiler is exceeded the spring gives and the valve closes, thereby cutting off the supply of fuel to the boiler until the boiler pressure returns to the normal working pressure.

To describe more fully, the fuel enters the primary combustion chamber "A" through the opening 5, the more volatile constituents of said fuel being in the form of a gaseous mixture. Combustion of the more volatile of said fuel takes place in the primary combustion chamber A, and the less volatile of said fuel is further heated toward volatilization and cracking by said heat within chamber A and by impact with fragments 7 and the bottom wall, and deflection against the sides, of said chamber A; thence the combustion constituents pass through the outwardly and upwardly inclined openings 8 in wall 4 where the less volatile of said fuel is further heated by the walls of openings 8 and further volatilized and cracked, and passed combusting into the secondary combustion chamber B, and discharged, at an angle to,

and in the direction of, the travel of the products in chamber B, against the corrugated wall of boiler 3, which, with said openings 8 being in a multiple of horizontal and vertical planes in said cylindrical wall 4, produce a progressive intermingling of the discharges from openings 8, thereby promoting progressive turbulence in chamber B, rapidity of flame propagation, combustion and fuel economy in close proximity to, and progressive contacts with, the wall of boiler 3, combustion in chamber B being furthered by the openings 46 inducting air therein in the direction which the contents of chamber B flow.

Thence, the combustion products pass over the adjacent end of boiler 3 and into the adjoining end of down-draft flue 10, surrounding the outer wall, and in direct contact throughout its length of, boiler 3; thence, the combusted products are passed over the opposite end of boiler 3, and the bottoms of chambers A and B, to a centrally disposed draft opening 47; the vertical baffles 9 in flue 10 promoting the equal distribution between each of said baffles of the draft of said opening 47.

The secondary combustion chamber B is of progressively increasing volume, in the direction of its outlet end, attained, in the instance shown in the drawings, by the converging wall 4 of the primary combustion chamber A, which, with the restricted area of flue 10, slows up the flow of the products through chamber B and increases relatively the aforesaid turbulence of the combusting products and prolongs their direct contacts with the inner surface of boiler 3.

In boilers of all types the accumulation and formation of so called scale on the inside walls of the water containing element causes a great deal of trouble and can be eliminated only by the use of pure water. In my invention I provide a method of and means for obtaining pure distilled water at all times for the boiler proper by incorporating in the walls of the casing 1, and displacing lining 2 to the extent thereof, a low pressure evaporating chamber or boiler 37, in direct contact with, and capable of absorbing heat from, the exhaust gases passing down the gas flue 10 between the coil of pipe forming the high pressure boiler 3 and the low pressure boiler 37, and capable of evaporating just enough water to make up the loss in feed water due to evaporation and leakage. In the outside walls of the low pressure boiler 37 I provide a detachable man-hole plate 39 which may be removed at any time for cleaning the scale from the evaporating unit 37 without disturbing any other part of the plant. Water is fed to the low pressure boiler 37 by gravity from a main supply tank 35 through a pipe 36 entering the lower part of the boiler 37. The

main supply tank 35 is placed on a level with reference to the low pressure boiler 37 so that all the water in the tank will enter the low pressure boiler as it is evaporated. When evaporation takes place the vapor exhausts through a pipe 38 leading from the top part of the low pressure boiler 37, through a float controlled valve 49 placed inside of a pure feed water tank 40, thence said vapor passes through pipe 42 leading to the top of a condenser 41 above the pure feed water tank. The vapor is then condensed to a degree just below the vaporizing point and passes in the form of pure water from the bottom of condenser 41 through a pipe 43 by gravity into the pure feed water tank 40. The valve 49 in the pure feed water tank 40 connects pipe line 38 with pipe line 42 leading to the condenser and is controlled by a float 44 that rises and falls with the water level in the pure feed water tank 40. Normally when the water level in the pure feed water tank 40 is at a predetermined level the float action keeps the valve 49 closed and prevents vapor entering the condenser. When the water level drops the float drops and opens the valve, permitting the vapor to enter the condenser and condense until the normal water level is again obtained. If the valve is closed and the pressure in the boiler 37 rises sufficiently, it forces all the water in the boiler back into the main supply tank 35 and no further evaporation takes place until the valve 49 opens and releases the pressure. It will be seen therefore that the pure feed water evaporating unit is designed to evaporate just enough make up water from tank 35 to replace the pure feed water lost in the operation of the plant.

I attain a further conservation of fuel and apparatus by the following means whereby the exhaust vapor from the main power generating plant is returned to, and enters the top of, the same aforesaid condenser 40, through an independent opening 45 in the top part of the condenser 41, condenses, and then passes into the pure feed water supply tank 40 through said same pipe 43 that also conveys to said tank 40 the condensation from boiler 37.

The apparatus for supplying the liquid to the high pressure boiler 3 is adapted to supply the liquid in varying quantities and in proportion to the variations in the demand for steam. While some of the advantages of my invention may be realized by the use of various types of generators in connection with the apparatus for supplying and controlling the liquid for the high pressure boiler, the best results can be obtained by the use of a boiler in which the liquid is gradually or progressively heated from its point of entrance to tank 35 to the point where it leaves the high pressure boiler as a superheated vapor and in which only a relatively

small quantity of the liquid is maintained at the temperature of vaporization corresponding to the pressure at which the boiler is to be operated. These conditions have been best realized by me in an apparatus 5 wherein a boiler consisting of a continuous pipe and described herein as a coiled pipe or boiler 3 encircling a combustion chamber and in which the gases of combustion pass 10 the coil in a direction with and then opposite to the flow of fluid within the coil.

Referring to the drawings Fig. 1, a feed pump 26 driven by the main engine or other power generating unit receives water from 15 the pure feed water tank 40 through a suction pipe 27 and discharges it through a pipe 28 into the main feed water pipe 11 connected to the boiler 3. The steam used by 20 the main power generating unit is supplied by the boiler 3 through a pipe 12 connecting the boiler with a double sweep T passage formed in a head block 13 which is the upper member of an automatic feed-water regulating device. The passages formed in the head 25 block 13 connect the boiler with a fuel control diaphragm regulator 14, previously described, and also connects the boiler with a pipe 20 containing a thermostat, or the metal of which pipe 20 may constitute said thermo- 30 stat; through which pipe 20, and connecting pipe 23, passes all the steam used by the main power generating unit. The head block 13 is connected by tie rods 21 and 22 to a lower supporting base 24, in which a passage is formed 35 connecting the pump discharge pipe 28 with the main feed pipe 11 leading to the boiler. Connecting the head block 13 with the thermostatic tube 20, is a valve 19 adapted to be turned off to prevent condensation of steam 40 in the tube 20 when steam is not being used by the main power generating plant. Incorporated in the supporting base 24 and in the passage connecting the pump discharge pipe 28 with the main feed pipe 11, is a by- 45 pass valve 25 connecting said passage with a return pipe 32, 33, connected with the intake of the pump 26. The by-pass valve 25 is opened and closed by its stem being longitudinally moved by the contraction and ex- 50 pansion of the thermostatic tube 20, a throttle valve, steam pipe 23 leading to the power generating unit as a means of throttling the steam. A safety by-pass check valve 29 connects the discharge pipe 28 of the pump 26 55 with the return pipes 32 and 33 thereby bypassing the water discharged from the pump 26 when the pressure in the boiler becomes excessive. A valve 29a may connect with the main feed-water pipe line 11, between 60 the check valve 30 and the boiler 3, with the return pipe line 32 and will act as a safety valve for the boiler when the pressure therein exceeds the working pressure by returning a 65 part of the water content of the boiler 3 through said valve and pipes 32, 33 and 27 to

tank 40. However, all of the fluid supplied to boiler 3, being near the vaporizing point, the volume of fluid therein under normal operating conditions is such that the capacity of airdome 31 will at all times adequately permit the withdrawal of enough fluid for safety from boiler 3.

A check valve 30 is provided in the main feed pipe line 11 between the boiler and the by-pass valve 25 to prevent the contents of the boiler escaping through the by-pass valve 25 when it is open. An air chamber or dome 31 is provided in the main feed pipe line 11 also, between the boiler and the check valve 30, to obtain an even and shockless circulation to the boiler when there is a sudden variation in the demand for steam. This air chamber or dome also acts as a storage for the water being pumped into the boiler, and when there is a sudden demand for steam and the pressure in the boiler drops, such as would happen in starting the main or any additional engine, the air in the chamber or dome forces the water in the air chamber into the boiler and keeps up the circulation in advance of the opening of check-valve 30 to admit water or other fluid that may be required from pump 26, when the pressure in said airdome 31 and boiler 3 falls below the point at which check-valve 30 is set to open toward boiler 3. The air chamber within its capacity, initially withdraws water from the boiler when the pressure suddenly becomes excessive as would be the case if the main or any engine were suddenly stopped after having been run at full speed.

To explain more fully, we will assume that the main engine is in operation by steam from pipe 23 and that the water pump 26 is connected with it and also is in operation. We will assume also that the by-pass valve 25, operated by the expansion and contraction of the tube 20, or the thermostat contained therein, leading from the boiler to the main steam line 23, is set to open full when the temperature of the steam being used by the main engine and passing through the tube 20 falls to 400 degrees and set to close fully when the temperature of the steam reaches a temperature of 600 degrees. If the amount of water being pumped into the boiler is greater than the amount of steam being used the water level will rise, also the pressure will rise. Should the pressure in the boiler exceed the maximum working pressure the safety by-pass valve 29 will open and the water being pumped will return to the intake side of the pump, and also to tank 40 when part of the content of boiler 3 is also discharging due to a temporary excess of pressure, through return pipes 32, 33 and 27. If the water level in the boiler rises too high in the boiler it will lower the temperature of the steam being used by the power generating unit, which will cause the thermostatic tube 20 to con-

tract and open the by-pass valve 25, and thereby by-pass the water back to the pump 26 through the return pipe 32, 33 and to circulate through said pump 20, as heretofore described. Should the water level in the boiler start falling the temperature of the steam being used by the main power generating unit will rise in proportion until it reaches the maximum of 600 degrees, at which time the 10 by-pass valve 25 will be closed by the expansion of the thermostatic tube 20 and cause more water to enter the boiler. Since the area of the opening in the by-pass valve varies in direct ratio to the temperature of the 15 steam being used by the main power generating unit, a time will occur while the steam is being used at a uniform rate, when the quantity of water entering the boiler will equal exactly the quantity of steam being 20 used.

The steam pressure is normally regulated by varying the supply of fuel according to the pressure in the boiler through the use of an automatic fuel valve 16 operated by a 25 regulating diaphragm 14 which is acted upon by the pressure in the boiler, but at times the pressure will rise suddenly, such as would be the case were the steam shut off suddenly from the main power generating 30 unit and the engine allowed to idle and operate the feed-water pump. In such cases the safety by-pass valve 29 will open and by-pass the water back to the pump intake.

When the boiler is empty and it is desired 35 to get up steam, water may be forced into the boiler by a hand pump until a sufficient quantity has been pumped to operate the main power generating unit to which the main feed-water pump is attached.

40 In accordance with the patent statutes, I have described what I now believe to be the best embodiment of my invention, but I do not wish to be understood thereby as limiting myself or the scope of my invention, as 45 many modifications may be made without departing from the spirit of my invention, and all such I aim to include in the scope of the appended claims.

The invention herein described may be 50 manufactured and used by or for the Government of the United States for governmental purposes without the payment to me of any royalty thereon or therefor.

What I claim as new and desire to secure by 55 Letters Patent is:

1. In the operation of vaporizing a fluid by heat, the method of controlling the supply of fluid to the vaporizing point consisting of the steps of supplying in a definite path from 60 its source the fluid to be vaporized; applying force to the fluid supply at a point in said path; connecting opposite ends of a fluid supply return path with said supply path at points on opposite sides of said force applying point; controlling the volume of said

fluid supply to the vaporizing point by regulating the communication between said pathways by a function of the vaporized fluid; further controlling the said supply to the vaporizing point, at a point between said first named control and the vaporizing point, by a function of the fluid in process of being vaporized; and still further controlling the said supply to the vaporizing point at a point between said first control and the point where force is applied to said fluid supply by at said point regulating the volume of the forced fluid supply that may be admitted from said supply path to said return path.

2. In the method of operation of vaporizing a fluid by heat, the steps of admitting the fuel to a smaller portion of a primary combustion zone of increasing area from said admission onward; igniting and combusting the more volatile constituents of the fuel in said zone; progressively passing the products of combustion from said first named zone at each of a plurality of points and into a smaller portion of a second zone of increasing area from each said admission onward; combusting the lesser volatile constituents of the fuel in said second named zone; transferring said combustion heat to a zone of fluid to be vaporized at a surface of said zone juxtaposed to one of said first two named zones; passing the combusted or combusting products along substantially the remaining surfaces of said fluid zone and thence exhausting said products.

3. In an apparatus for vaporizing a fluid the combination of an apertured wall of refractory material forming the lateral boundaries of a primary combustion chamber; walls of refractory material forming the end walls of said primary combustion chamber; a fuel inlet into said primary combustion chamber through one of said end walls; a wall of thermally conductive material forming with the said apertured wall a secondary combustion chamber, said thermally conductive material forming the external boundaries of a container for said fluid; a wall of thermally insulative material surrounding said wall of thermally conductive material and forming with it a flue space connecting with one end of said secondary combustion chamber; means for supplying fuel to said fuel inlet and means for supplying fluid to said container.

4. In an apparatus for vaporizing a fluid the combination of an apertured wall of refractory material forming the lateral boundaries of a primary combustion chamber of continuously increasing cross-sectional area; walls of refractory material forming the end walls of said primary combustion chamber; a fuel inlet into said primary combustion chamber through one of said end walls; a wall of thermally conductive material forming with said apertured

wall a secondary combustion chamber of continuously increasing cross sectional area; said thermally conductive material forming the external boundaries of a container for said fluid; a wall of thermally insulative material surrounding said wall of thermally conductive material and forming with it a flue space connecting with one end of said secondary combustion chamber; means for supplying fuel to said fuel inlet and means for supplying fluid to said container.

5. In the operation of vaporizing a liquid, the method of fuel and apparatus conservation which consists in vaporizing a fluid under substantially atmospheric pressure in a vaporizing zone substantially juxtaposed to a heating zone; condensing said vapor under substantially atmospheric pressure in a condensing zone; leading said condensed vapor 15 to and revaporizing the same in a separate vaporizing zone juxtaposed to said heating zone and under a pressure greater than atmospheric pressure; and supplying exhaust vapor to the herein constituted system substantially at the entrance to said condensing zone.

6. In the operation of vaporizing fluids, the method of fuel and apparatus conservation consisting of combusting fuel in a heating zone; revaporizing under a pressure greater than atmospheric pressure previously condensed vapor in a vaporizing zone substantially juxtaposed to said heating zone and by some of said combustion heat; supplying exhaust vapor to and condensing the same under substantially atmospheric pressure in a condensing zone; returning said condensed vapor to and revaporizing the same in said vaporizing zone; separately 20 vaporizing in a separate vaporizing zone juxtaposed to and by some of the heat of said heating zone and under substantially atmospheric pressure enough make-up fluid to supply operation losses; and conveying the vaporized make-up fluid to and condensing the same in said condensing zone.

7. In the operation of vaporizing a fluid by heat, the method of controlling the supply of fluid to the vaporizing point consisting of 25 the steps of associating a fluid vaporizing area and a fluid supply area, leading fluid in a supply pathway from the supply to said vaporizing area, connecting opposite ends of a return pathway with said supply pathway at points intermediate said areas, continuously applying force to said fluid in said supply pathway at a point between the ends of said return pathway, controlling the supply of fluid to the vaporizing area at a point 30 between said vaporizing area and the adjacent end of said return pathway by the relative force applied to the fluid and the pressure of the fluid being vaporized; controlling the supply of fluid to the vaporizing area by 35 regulating by a function of the vaporized

fluid the area of the return pathway connecting the supply pathway nearest the vaporizing point; and further controlling the supply of fluid to the vaporizing point by regulating the bypassing of the fluid from the supply pathway to the return pathway at a point toward the vaporizing area from the point of application of said force.

8. In an apparatus for vaporizing fluid by heat, the combination of a vaporizer, piping for supplying fluid to the vaporizer for vaporization therein, a pump connected to said piping, a branch pipe having its opposite ends connected to said piping on opposite sides of said pump, a valve controlling the inlet to said branch pipe at its end nearest the vaporizer, means for controlling said valve by a function of the fluid vaporized by the vaporizer, means between said valve and vaporizer for controlling the supply of fluid to the vaporizer by a function of the fluid being vaporized, and a check valve controlled bypass between said piping and branch pipe at a point intermediate said pump and the first stated valve.

9. In an apparatus for vaporizing fluid by heat, the combination of a vaporizer, piping for supplying fluid to the vaporizer for vaporization therein, a pump connected to said piping, a branch pipe having its opposite ends connected to said piping on opposite sides of said pump, a valve controlling the inlet to said branch pipe at its end nearest the vaporizer, means for controlling said valve by a function of the fluid vaporized by the vaporizer, means between said valve and vaporizer for controlling the supply of fluid to the vaporizer by a function of the fluid being vaporized, a check valve controlled bypass between said piping and branch pipe at a point intermediate said pump and the first stated valve, means for supplying fuel to heat the vaporizer, and means regulated by a function of the vaporized fluid for controlling the supply of fuel to the vaporizer.

10. In an apparatus for vaporizing fluid by heat, the combination of a vaporizer, a supply pipe adapted to lead fluid to the vaporizer, a branch pipe connected to said pipe, an outlet pipe leading from the vaporizer and extending to a point adjacent the point of connection of the branch and supply pipes, a thermostatic valve stem extending into said outlet pipe and adapted to close the branch pipe proportionate to the heat of the content of said outlet pipe, and means for rigidly connecting said supply and outlet pipes adjacent said valve stem.
